FIG. 1.

FIG. 2.

FIG. 3.

FIG. 4.

FIG. 5.

FIG. 6.

FIG. 1 is a front elevational view of a box showing my new design;

FIG. 2 is a rear elevational view;

FIG. 3 is a side elevational view looking from the right of FIG. 1;

FIG. 4 is an elevational view showing the side opposite that seen in FIG. 3;

FIG. 5 is a top plan view; and

FIG. 6 is a bottom plan view thereof.

The circular formation illustrated in the top plan view of FIG. 5 is a dispensing opening which becomes operative to dispense from the box when the box top is moved in a sliding relationship from left to right when viewing the box as illustrated in FIG. 2. The oval formation illus-

trated in the bottom plan view of FIG. 6 is merely a decorative concavity corresponding to the shading in FIG. 6.

I claim:

The ornamental design for a box, as shown and described.
